ADJUSTABLE TRUSS PAD

John C. M. Shaw, Mangum, Okla.

Application January 10, 1936, Serial No. 58,569

2 Claims. (Cl. 128—116)

The invention aims to provide a new and improved truss pad which may be easily adjusted to obtain the desired pressure at any required point without the necessity of having the pad-carrying strap as tight around the body as now required.

A further object is to provide a novel construction whereby the pad may be quickly and easily adjusted forwardly or rearwardly with respect to the belt, according to the requirements.

10 Another object is to provide novel means for rearwardly pressing a restricted part of the body-engaging portion of the pad to provide a convex projection thereon adapted to hold internal parts of the body against outward movement into a rupture, allowing the rupture to heal.

Yet another object is to provide a construction which may be easily and inexpensively manufactured, may be sold at small cost, may be easily adjusted by the wearer, and will afford a maximum amount of comfort.

20 With the foregoing in view, the invention resides in the novel subject matter hereinafter described and claimed, description being accomplished by reference to the accompanying drawings.

25 Fig. 1 is a top plan view showing two of the improved pads mounted upon a belt, showing different adjustments of said pads.

Fig. 2 is an enlarged central sectional view 30 through one of the pads on line 2—2 of Fig. 1.

Fig. 3 is a perspective view of the front plate which is secured to the belt.

Fig. 4 is a perspective view of the flanged disk which is adjustably threaded upon the front 35 plate, and the cup adjustably mounted on said disk.

Fig. 5 is a perspective view of the dome-shaped elastic pad which is connected with the aforesaid disk and abuts a resilient body held by said cup.

40 Two of the pads are shown connected with a conventional leather-covered steel belt B whose ends are connected by a strap S, said belt being provided with the usual spaced openings to facilitate attachment of the pads. As both pads are 45 of identical construction, only one will be described.

I provide a front plate 8 for attachment to the belt B, said plate having a threaded edge 9. This plate is attached to the belt by a short 50 bolt 10 whose nut 11 is held by ribs 12 on said plate. This plate is held against rotating about the bolt 10, by suitable lugs 13 which are formed on the front side of said plate and abut the upper and lower edges of the belt B.

55 Behind the front plate 8 is a disk 14 whose

front side is provided with a continuous flange 15 having internal screw threads 16 engaged with the screw threads 9 of the front plate 8, so that said disk 14 may be adjusted forwardly or rearwardly by rotating it. The rear side of the disk 5 14 is provided with a continuous undercut flange 17 which engages and holds a flange 18 on the edge of an elastic dome-like pad 19, this pad being formed from rather soft rubber.

Mounted upon the central portion of the disk 10 14 and disposed behind this disk, is a cup 20 which is of much smaller diameter than said disk. A yieldable body 21, preferably a small sponge rubber ball, is held in the cup 20 and projects rearwardly therefrom into contact with 15 the central portion of the dome-like pad 19, said central portion being preferably thinner than the remainder of said pad. Provision is made for forwardly and rearwardly adjusting the cup 20 as may be desired, and the more this cup is rearwardly adjusted, the harder it forces against the central portion of the pad 19, with the result that said central portion may be forced rearwardly to form a small convex projection 22 to press upon the user's flesh directly in line with the rupture 25 so as to effectively hold internal parts of the body against outward movement into said rupture, allowing the latter to readily heal.

In adjustably mounting the cup 20, I provide 30 screw threaded adjusting means so that said cup may be adjusted forwardly or rearwardly, simply by rotating it. In the present showing, a stud 23 is centrally secured at 24 to the disk 14 and projects rearwardly from said disk, the cup 20 being threaded upon said stud as shown at 25.

35 By rotating the flanged disk with respect to the front plate 8, said disk, the dome-like pad 19, and parts within this pad, may be bodily adjusted forwardly or rearwardly as required. By disconnecting the pad 19 from the disk 14, the cup 20 40 is accessible and by rotating this cup, it may be adjusted forwardly or rearwardly to suit the exigencies of the case. The pad 19 may then be readily reconnected with the flange 17 simply by snapping its flange 18 into engagement with said flange 17.

45 It will be seen from the foregoing that novel and advantageous construction has been provided for carrying out the objects of the invention. While preferred details have been shown, variations may be made within the scope of the invention as claimed. Moreover, any desired material or materials suited to the purposes which they must fulfill, may be employed, and the sizes and 50 55

proportions of parts may be varied within a wide range.

I claim:—

- 5 1. In an adjustable truss pad, a front plate for attachment to a belt, a disk behind said front plate and having a threaded connection therewith to allow forward and rearward adjustment of said disk by rotating the same, a rearwardly open cup behind said disk and having a threaded connection therewith to allow forward and rearward adjustment of said cup by rotating it, said cup being of much smaller diameter than said disk, a yieldable body seated in and projecting rearwardly from said cup, and a dome-like yield-
- 10 able pad enclosing said yieldable body and con-
- 15

tacting with the rear side thereof, the edge of said dome-like pad being connected with said disk.

2. In an adjustable truss pad, a disk and means for mounting it on a belt, a rearwardly open substantially hemispherical cup mounted on the rear side of said disk, a substantially spherical elastic body seated removably in said cup and projecting rearwardly therefrom, and a dome-like elastic pad enclosing said elastic body and detachably secured to said disk, said dome-like elastic pad being free of connection with said substantially spherical elastic body but disposed in abutting relation therewith to hold said body in said cup.

JOHN C. M. SHAW. 15
